United States Patent Office

Des. 227,510
Patented June 26, 1973

227,510

HOLDER FOR A PEN AND PAPER

Anthony J. Pisciotto, 10439 W. Medill Ave.,
Melrose Park, Ill. 60164

Filed June 1, 1972, Ser. No. 258,948

Term of patent 7 years

Int. Cl. D19—02
U.S. Cl. D74—5 A

FIG. 1 is a perspective view showing my new design for a holder for a pen and paper;

FIG. 2 is a front elevational view thereof;

FIG. 3 is a side elevational view thereof;

FIG. 4 is a top plan view thereof;

FIG. 5 is a bottom plan view thereof; and

FIG. 6 is a rear elevational view thereof.

I claim:

The ornamental design for a holder for a pen and paper, as shown.
